BEST AVAILABLE COPY CLUTCH-SPRING COMPRESSOR.

1,286,933.

Specification of Letters Patent. Patented Dec. 10, 1918.

Application filed January 7, 1818. Serial No. 210,788.

To all whom it may concern:

Be it known that we, JESSE L. BURNS and JOHN J. WILSON, citizens of the United States of America, and residents of Farnhamville, Calhoun county, Iowa, have invented a new and useful Clutch-Spring Compressor, of which the following is a specification.

The object of this invention is to provide an improved device for compressing a spring held under tension by a pin which it is desired to remove.

A further object of this invention is to provide an improved device adapted for use in dismantling the clutch devices employed on certain makes of motor vehicles, viz: Chevrolet 490.

Our invention consists in the construction, arrangement and combination of elements hereinafter set forth, pointed out in our claims and illustrated by the accompanying drawing, in which—

Figure 1 is a side elevation, partly in section, showing our improved device in position for use on a clutch member from which it is desired to remove a pin and spring. Fig. 2 is an outer end view of the same. Fig. 3 is a central longitudinal section at right angles to the showing of Fig. 1, certain parts of the device being shown in altered position.

In the construction and application of the device the numeral 10 designates a sleeve which forms a part of one member of a clutch employed on a certain type of automobiles, as for instance the "Chevrolet," said sleeve having mounted within an expansive coil spring 11 adapted normally to hold the coacting clutch member (not shown) out of engagement; said sleeve also having a pin 12 mounted transversely therethrough near one end and forming a stop for the spring 11. The spring 11 is under tension against the pin 12 which renders it difficult to remove said pin when it is desired to dismantle the clutch devices for any purpose such as repair, and it is our purpose to provide a device or tool for compressing said spring away from said pin to permit withdrawal of the pin, after which the spring and other parts of the device may be removed.

The sleeve 10 also is formed with a peripheral flange 18 at its end formed with a plurality of tapped bolt holes 14 arranged in diametrically opposed pairs.

In the construction of the tool itself a bar 15 is provided, of a length corresponding approximately to the diameter of the flange 18, and bolts 16, 17 are mounted loosely through opposite end portions of said bar, said bolts being adapted to be mounted selectively in a pair of the holes 14 to position the device for use. A collar 18 is swiveled loosely on one side of and at the center of the bar 15, a rivet 19 being mounted through the bar and having a head on one end preventing passage through the bar and on the other end a disk upon which the collar is shrunk or otherwise securely fixed. The collar 18 is open at its free end and is adapted to fit loosely within the end of the sleeve 10, and is formed with diametrically opposite end opening notches or slots 20, 21 adapted to fit over the pin 12 and permit passage of the end of the collar beyond said pin and into contact with the end of the spring 11. Nuts 22, 23 are screwed on the bolts 16, 17, between the heads of said bolts and the bar 15, and are adapted to be screwed downwardly on said bolts to apply pressure to said bar.

In practical use the nuts 22, 23 are first loosened on the bolts 16, 17, that is to say moved toward the heads of said bolts. The collar 18 is inserted within the open end of the sleeve 10 and the notches or slots 20, 21 caused to straddle the pin 12. Then the bar 15 is turned, on the rivet 19, so that the ends of the bolts 16, 17 may be caused to enter a pair of the bolt holes 14, and said bolts are then turned sufficiently to securely seat them in such holes, and hold the device in the position shown. Then the nuts 22, 23 are screwed down into contact with the outer face of the bar 15 and are then further turned to apply pressure to said bar. This has the effect of applying pressure, through the collar 18, to the spring 11, to the end of compressing said spring away from the pin 12, and when the pressure of the spring on the pin is released the pin may be readily and conveniently withdrawn from its seat. Then the device is removed, by loosening the nuts 22, 23 and unseating the bolts 16, 17, after which the spring and other parts of the device may be removed, as desired for the work in hand.

The device may be used in a similar manner to compress the spring for the insertion of the pin, in assembling the clutch device.

We claim as our invention—

1. A device of the class described, compris-

2. ~~1,286,933~~ 1,286,933 PATENT OFFICE

- ing a bar, a collar swiveled thereto, said collar bolts loosely extend, a spring-engaging member being adapted to straddle a pin and engage a spring, means for securing said bar, said member being slotted at its end to 25
5 pressure to said bar, and nuts threaded on said bar.
2. A device of the class described, comprising a support, a spring-engaging member swiveled thereto, said spring-engaging member being formed with a slot to straddle a pin, means for securing said support in desired position, and means for applying pressure to said support.
3. A device of the class described, comprising a pair of supporting bolts, a supporting bar loosely mounted on said bolts, a spring-engaging member swiveled to the central portion of said bar, and nuts threaded on said bar.
4. A device of the class described, comprising a pair of supporting bolts, a supporting bar through end portions of which said
5. A spring-compressing device adapted for use on a sleeve containing an expansive 30 pin, said sleeve being formed with a peripheral flange having tapped bolt holes diametrical, arranged, said device comprising a pair of bolts adapted to be seated in said tapped holes, a bar loosely mounted on said bolts, a spring-engaging member swiveled to the central portion of said bar and adapted to enter said sleeve, said member being forked at its end to embrace said pin, and nuts threaded on said bolts and adapted to engage and apply pressure to said bar.

JESSE L. BURNS.

JOHN J. WILSON.
